UNITED STATES PATENT OFFICE.

HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,297,757.

Specification of Letters Patent. Patented Mar. 18, 1919.

Application filed November 10, 1917. Serial No. 201,279.

To all whom it may concern:

Be it known that I, HENRY G. VOIGHT, a citizen of the United States, residing in New Britain, county of Hartford, and State of Connecticut, have invented certain new and useful Improvements in Locks, of which the following is a full, clear, and exact description.

This invention relates to locks, and more particularly to extensible cylinder locks which are adjustable for application to doors of different thickness. The primary object of the invention is the production of an extensible lock which permits a maximum range of adjustment with comparatively few parts, the parts being so constructed that a material increase is obtained in the length of the bearings for the guide pins and adjustable screw over the type of extensible locks now in general use, without decreasing the range of adjustment.

Another object of the invention is to simplify and improve the mechanism by which the extension is adjustably secured to the main part of the lock.

To these and other ends, the invention consists in the novel features and combinations of parts to be hereinafter described and claimed.

30 In the accompanying drawing:

Figure 1 is a side elevation of a cylinder lock embodying my improvement, showing the lock partly extended;

Fig. 2 is a similar view from the opposite 35 side of the lock;

Fig. 3 is an elevation of the lock shown in Fig. 1, looking in the direction of the arrow, the lock being shown in its shortest adjustment and the extension being shown 40 as cut by a section taken substantially on the line 3—3 of Fig. 5;

Fig. 4 is a rear end view of the main part of the lock, the extension with its guide pins and adjusting screw being removed;

45 Fig. 5 is a view showing the inner face of the extension with the pins and adjusting screw secured thereto.

My improved cylinder lock comprises a main part or cylinder lock proper 10, and 50 an extension 11 detachably connected therewith. The main part 10 is, for the most part, of usual construction, having a case 12, a face plate or escutcheon 13, a pin tumbler extension 14, and the usual key plug or barrel (not shown) inside of the case 12, which

barrel is locked against rotation by the usual pin tumblers, (not shown). In the embodiment illustrated, the lock proper 10 is provided with a plurality of lugs 15, 16 and 17 rigidly formed upon the inner end of the main part of the lock, and so positioned that they project beyond the rear end of the part of the lock to which they are secured. The lug 15 is provided with a threaded drill hole 18 and the lugs 16 and 17 are provided with smooth drill holes 19 and 20. The key barrel, which is not shown, is provided with the well-known washer 21, which may be secured to its barrel by means of screws 22. The lugs 16 and 17 are partially cut away in order to provide a clearance space in which the washer 21 rotates.

The detachable extension 11 for the cylinder lock may consist of a shell-like head 23 provided with the usual threads upon its periphery, by which the cylinder may be secured to the case of the mortise lock. This head 23 is preferably made by stamping sheet metal up in the cup-shaped form shown in Fig. 3. However, it will be apparent that my invention is not necessarily limited to this particular type of head. The extension 23 is provided with a plurality of smooth guide pins 24 and 25, which are rigidly mounted in the head and project therefrom at right angles to the face of the same. The head 23 is further provided with an adjusting screw 26. This screw is rotatably mounted in the head and is held against longitudinal movement in one direction relatively to the head by the tapered head of the screw being seated in a correspondingly tapered countersunk opening in the extension head, and the screw is held against longitudinal movement in the opposite direction by a washer 27, which washer is secured in place on the screw by upsetting a portion of the screw around the washer. The head of the screw is provided with the usual screw-slot, by means of which the screw may be rotated.

The head 23 is provided also with the well-known roll-back 28, which may be conveniently operated by means of a pair of pins 29, 30, rigidly secured thereto. The roll-back 28 is held against longitudinal movement relative to the head by a washer 31 rigidly secured thereto and mounted inside of the head 23. The washer 21, which is mounted on the key barrel (not shown)

is provided with drill holes 32 and 33. These holes extend almost entirely through the key barrel and operatively receive the projecting pins 29, 30.

5 From the construction already described, it will be apparent that the extension 11 is adjustably mounted upon the main part of the lock by the smooth guide pins 24, 25, and that the extension may be adjusted to 10 any desired position relatively to the main part of the lock by the adjusting screw 26. The roll-back 28 will be operatively connected to the key-operated barrel in any adjustment of the extension by the projecting pins 29, 30, which are slidably received in the openings 32, 33 and in the key barrel.

The shell-like structure of the head 23 forms a housing in which the lugs 15, 16 and 17 project, when the parts assume the position shown in Fig. 3, the arrangement being such that when the lock is given its shortest adjustment, the head will not abut against the ends of the lugs, but the lugs will project into the shell-like head while the rim 25 of the head abuts against the inner face of the main part of the lock.

By constructing my lock so that the lugs are permitted to project within the head of the extension, I am able to materially increase the length of the bearings for the pins 24, 25 and the bearing of the adjusting screw 26, without decreasing the range through which the extension 11 may be adjusted. Furthermore, this arrangement by which the 30 ends of the lugs may project into the head 23 enables me to obtain a range through which the extension may be adjusted, greater than the entire length of the main part of the lock, it being apparent that as the length 35 of the lugs is increased beyond the end of the main part of the lock, the range of adjustment is correspondingly increased, provided the lugs are permitted to project into the extension. In other words, by extending 40 the lugs beyond the end of the main part of the lock, I form what may be termed a telescopic adjustment between the sliding pins and the lugs, thereby increasing the range 45 of adjustment in proportion to the extent the lugs are permitted to project into the head 23.

In order to form a clearance space for the ends of the pins 24, 25 and adjusting screw 26 when the extension assumes its shortest 50 adjustment, the escutcheon 13 is provided upon its inner face with recesses or sockets 34 into which the ends of the pins just mentioned may extend.

It will be apparent from the above description of my extensible lock that I have devised a simple, serviceable lock which permits of a long range of adjustment for the extension and which at all times provides a strong, firm supporting connection between 60 the main part of the lock and its extension.

Without limiting myself to the construction shown, I claim:

1. An extensible cylinder lock comprising a main part and an extension adjustably connected thereto, a guide pin rigidly secured to said extension, and a pin-receiving lug formed rigidly upon the main part of the lock, said lug being positioned to extend beyond the main part of said lock into the extension. 70

2. An extensible cylinder lock comprising a main part and an extension adjustably connected thereto, supporting means secured to said extension and projecting therefrom, and a lug coöperating with said supporting means, formed upon said main part, said lug being positioned to extend beyond the main part of said lock into the extension. 75

3. An extensible cylinder lock comprising a main part and an extension adjustably connected thereto, an adjusting screw rotatably mounted in said extension, a threaded lug for said screw rigidly formed upon said main part, said lug being positioned to extend beyond the main part of said lock 80 and into said extension when the lock is extended its minimum distance. 90

4. An extensible cylinder lock comprising a main part and an extension adjustably connected thereto, an adjusting screw for said extension, and a lug for said screw mounted upon said main part and positioned to project beyond the end of the main part of the lock into the extension, whereby the length of the lug is increased without decreasing the range of the adjustment of the extension. 95

5. An extensible cylinder lock comprising a main part and an extension adjustably connected thereto, guide pins rigidly secured to said extension, and pin-receiving lugs formed rigidly upon the main part of the lock, said lugs and pins being arranged to permit a range of adjustment of the extension greater than the entire length of the main part of the lock. 105

6. An extensible cylinder lock comprising a main part and an extension, and means for adjustably securing the extension to the main part of the lock, said means constructed to permit a range of adjustment of the extension greater than the entire length of the main part of the lock. 110

7. An extensible cylinder lock comprising a main part and an extension, and means for adjustably securing the extension to the main part of the lock, said means being constructed to permit a range of adjustment of the extension equal to the entire length of the main part of the lock, said adjustable means operatively supporting the extension throughout the entire range of adjustment. 120

8. In combination with an extensible cylinder lock, means for adjustably mounting the extension upon the main part of the lock, 125

130

said means constructed to permit a range of adjustment greater than the entire length of the main part of the lock.

9. In combination with an extensible cylinder lock, means for adjustably mounting the extension upon the main part of the lock, said means constructed to permit a range of adjustment equal to the entire length of the main part of the lock and said adjustable means supporting the parts of the lock in their proper relation throughout the entire range of adjustment.

10. An extensible cylinder lock comprising a main part and an extension, and lugs formed integral upon the main part of the lock for adjustably supporting the extension, said lugs positioned to be partly housed by the extension when the lock is extended its minimum distance.

11. An extensible cylinder lock having a main part, and means upon said main part for supporting an extension, said means comprising integral lugs extending beyond the end of said main part into the extension, whereby the length of the lugs is increased without decreasing the range through which the extension may be adjusted.

12. An extensible cylinder lock comprising a main part and an extension adjustably connected thereto, guide pins rigidly secured to said extension, and pin-receiving lugs formed rigidly upon the main part of the lock, said lugs being positioned to extend beyond the end of the main part of the lock into the extension, whereby the length of the bearing of the guide pins in the lugs is increased.

13. An extensible cylinder lock comprising a main part having an escutcheon formed at one end thereof, and an extension adjustably connected to said main part, said extension having rigid supporting means extending therefrom, lugs integral upon said main part for adjustably receiving said means, said lugs being positioned to extend beyond the end of said main part, said es-

cutcheon having sockets formed in its face to receive the ends of the supporting means.

14. An extensible cylinder lock comprising a main part having an escutcheon formed at one end thereof, and an extension adjustably connected to said main part, said extension having rigid supporting means extending therefrom, lugs integral upon said main part for adjustably receiving said means, said escutcheon having sockets formed in its inner face to receive the ends of the supporting means.

15. In an extensible cylinder lock comprising a main part and an extension, guide pins secured to said extension to adjustably support the same, pin-receiving lugs formed rigidly upon the main part of the lock, and having pin-receiving openings therethrough, said lugs extending beyond the end of the main part of the lock, whereby a material increase in the length of the bearing for the pins is provided without decreasing the range of adjustment.

16. An extensible cylinder lock comprising a main part and an extension, means for adjustably securing said extension to the main part of said lock, comprising guide pins secured to said extension and pin receiving lugs upon said main part, said lugs being positioned to extend beyond the end of said main part into said extension, whereby the range of adjustment of said extension is increased.

17. An extensible cylinder lock comprising a main part and an extension, means for adjustably securing said extension to the main part of said lock, comprising guiding means secured to said extension and guide receiving means upon said main part, said guide receiving means being positioned to extend beyond the inner end of the main part of said lock.

In witness whereof, I have hereunto set my hand on the 7th day of November, 1917.

HENRY G. VOIGHT.
